UNITED STATES PATENT OFFICE.

DANIEL M. PFAUTZ, OF PHILADELPHIA, PENNSYLVANIA, ASSIGNOR OF THREE-EIGHTHS TO REINHART K. BARRETT, OF SAME PLACE, AND RURIC N. ADAMS, OF CAMDEN, NEW JERSEY.

SPRING-MOTOR FOR SEWING-MACHINES.

SPECIFICATION forming part of Letters Patent No. 417,081, dated December 10, 1889.

Application filed January 19, 1889. Serial No. 296,845. (No model.)

To all whom it may concern:

Be it known that I, DANIEL M. PFAUTZ, a citizen of the United States, and a resident of Philadelphia, Pennsylvania, have invented 5 certain Improvements in Spring-Motors for Sewing-Machines, of which the following is a specification.

The object of my invention is to so construct a spring-motor for sewing-machines 10 that any desired amount of power can be imparted to the driving-shaft of the machine. This object I attain in the manner herein-after set forth, reference being had to the accompanying drawings, in which—

15 Figure 1 is an end view of a sewing-machine with my improved spring-motor applied thereto, the spur-wheels being shown mostly in outline, with teeth only at the actual meshing-points. Fig 2 is a section on 20 the line 1 2, Fig. 1. Fig. 3 is a rear view of the motor, and Fig. 4 is a detached view of a portion of the same.

A A are the opposite end frames of the machine, in which are formed bearings for a 25 series of spring-shafts B D I J, intermediate frames E and F being also provided, which, however, are of less dimensions than the end frames A A, as they only serve to carry shafts at the rear portion of the machine. Each of 30 the spring-shafts carries in the present instance a series of small springs x, the inner end of each of which is secured to the shaft, while its outer end is secured to a fixed rod x', carried by the frames, so that on turning

35 the spring-shaft in one direction its springs will be wound up and on releasing the shaft the resiliency of the springs will cause the turning of the same in the opposite direction.

A series of small springs on each shaft is employed in preference to a single or small number of large springs, because of the greater cheapness of the small springs and the greater readiness of replacing one of them when broken or defective.

45 On the shaft B is a loose spur-wheel b, and gearing into said spur-wheel is a pinion b' on a shaft b², which is squared or otherwise formed at the end for the reception of a crank, whereby the turning of the shaft is 50 effected when it is desired to wind up the

springs of the shaft B. In like manner the spring-shaft D is wound by gearing d d' and shaft d², the spring-shaft I by gears i i' and shaft i², and the spring-shaft J by gears j j' and shaft j².

The shaft B has a spur-wheel b', which has the usual ratchet-and-pawl connection with the shaft, as shown in Fig. 4, so that the shaft can turn independently thereof when the springs are being wound up, the wheel 60 turning with the shaft in the opposite direction. This wheel B' gears into a pinion B² on a counter-shaft B³, adapted to bearings in the frames A and F of the machine, and the shafts D, I, and J are provided with like 65 gears and counter-shafts lettered to correspond with their respective spring-shafts.

G is the driving-shaft of the machine, having a pulley G', connected by a belt g to the pulley G² on the main shaft of the machine, 70 and said driving-shaft G has a pinion G³, which gears into a spur-wheel H' on a power-transmitting counter-shaft H, which has as many loose pinions h as there are spring-shafts, each of these pinions carrying one half 75 of a clutch, the other half of which is formed on a sleeve m, sliding on but splined to the shaft H and controlled by an arm m' on a shaft m², which is adapted to bearings in a suitable bar m³ of the frame and has at the 80 front end a handle m⁴, so that it can be readily operated by the attendant to throw its pinion into or out of engagement with the shaft H.

The counter-shaft B³ of the spring-shaft B 85 has a spur-wheel B⁴, gearing into one of the pinions h, and the counter-shaft D³ of the spring-shaft D likewise has a spur-wheel D⁴, gearing into one of the pinions h; but the movement of the counter-shaft I³ is transmitted to its corresponding pinion h by means of a spur-wheel I⁴ on the counter-shaft and an intermediate spur-wheel I⁵, loose on the counter-shaft D³, while the movement of the lowest counter-shaft J³ is transmitted to its 90 proper pinion h through the medium of a spur-wheel J⁴ on the shaft and two intermediate loose spur-wheels J⁵ and J⁶, located, respectively, on the shafts I³ and D³. It will thus be seen that by a proper adjustment of the 100

clutches m the power of any one or more of the spring-shafts may be transmitted to the driving-shaft of the machine, the power of the separate spring-shafts being exerted in 5 succession when moderate and long-continued power is required, or the power of all the shafts being exerted simultaneously when necessary.

The stopping and starting of the machine 10 are controlled by a friction-brake consisting of a drum n on the shaft H , having a brake-strap n' , the ends of which are connected to two arms of a three-armed lever K , the third arm of which is acted on by a spring n^2 , tending 15 to apply the brake, and by a rod n^3 , connected to a treadle M , on depressing which the brake will be released.

In order to prevent the running away of 20 either of the spring-shafts when it is disconnected from the shaft H , each of said shafts has a friction-brake similar to that of the shaft H , the lever K of each of these brakes being connected by a rod p to an arm p' on a shaft p^2 , which extends to the front 25 end of the machine and has an operating-

handle p^3 and retaining-ratchet p^4 , so that the brake-lever can be held either in the retaining or releasing position.

Having thus described my invention, I claim and desire to secure by Letters Patent— 30

1. The combination of the driving-shaft, clutch-pinions on said shaft, a series of spring-shafts, and gearing for connecting each of said spring-shafts to one of the clutch-pinions on the transmitting-shaft, substantially as 35 specified.

2. The combination of the driving-shaft, the power-transmitting shaft geared thereto, clutch-pinions on said shaft, a series of spring-shafts each having a friction-brake, and gearing connecting each of said spring-shafts to one of the clutch-pinions of the transmitting-shaft, substantially as specified. 40

In testimony whereof I have signed my name to this specification in the presence of two sub- 45 scribing witnesses.

DANIEL M. PFAUTZ.
